Patented Dec. 9, 1975

237,926

COMBINED SOAP DISH, TOOTHBRUSH HOLDER, AND TUMBLER

Barbara Adler Katzander, New York, N.Y., assignor to Joseph A. Kaplan & Sons, Inc., Yonkers, N.Y.

Filed Feb. 27, 1975, Ser. No. 553,755

Term of patent 14 years

Int Cl. D23—02

U.S. Cl. D6—91

FIG. 1

FIG. 2

FIG. 3

FIG. 1 is a side elevational view of a combined soap dish, toothbrush holder, and tumbler showing my new design;

FIG. 2 is a top plan view;

FIG. 3 is a bottom plan view;

FIG. 4 is an exploded perspective view; and

FIG. 5 is a vertical cross-sectional view.

I claim:

The ornamental design for a combined soap dish, toothbrush holder, and tumbler, substantially as shown.
